UNITED STATES PATENT OFFICE

JOSEPH F. SANFTLEBEN, OF NEW YORK, N. Y., ASSIGNOR TO JOHN H. LIDGERWOOD, JAMES G. LIDGERWOOD, C. F. FOX, ALL OF NEW YORK CITY, N. Y., AND BORIS KITCHIN, OF SAN MATEO, CALIFORNIA, DOING BUSINESS AS A SYNDICATE UNDER THE NAME OF FILTRATORS COMPANY

METHOD OF MAKING MUCILAGINOUS EXTRACT FROM SEEDS

Application filed January 29, 1926. Serial No. 84,795.

My present invention relates to improvements in methods for extracting the mucilaginous constituents of seeds, particularly flaxseed, such extract having a particular utility in the treatment of the water in steam boilers and the like for the prevention of the deposition of solids from such water.

At the present time, there is in use a method of preventing incrustation in boilers, in which vegetable seeds, usually flax, are subjected to steam under the pressure of the boiler to take out the mucilaginous constituents of the seeds, the extract being delivered directly into the boiler from which the extracting steam is derived, so that both the inlet and the outlet of the closed container in which the extraction takes place, are under substantially the boiler pressure.

Certain disadvantages arise from this arrangement and method. For instance, objection is made to the making of unnecessary openings in the boiler pressure parts, which, of course, is necessitated if the extract is to be returned directly into the boiler. Then, too, the operation of the extractor is not capable of complete observation as to its action.

My present invention is an improvement in the method now in use and described above and also in the British patent to Kobseff No. 176,294, in that, instead of delivering the fluid, which results from the treatment of the flaxseed or the like with steam and water, directly into the boiler, the water of which is to be treated, I provide means by which the fluid is permitted to flow into another vessel at a materially lower pressure than that of the closed vessel used in such method but without permitting the pressure in the closed vessel to drop materially.

In the annexed drawing I have shown an arrangement embodying my novel apparatus by which my method may be carried out.

In the illustrative arrangement, 10 is a boiler or a pressure portion of a steam boiler, the steam space of which is connected through a pipe 11 with a closed vessel 12 having a perforated container 13 in which the seeds from which the extract is to be obtained are placed. Fins 14 may be provided to afford

heat radiation surfaces to lower the temperature of the contents of the closed vessel.

An outlet pipe 15 connects with the lower portion of the vessel 12 and is provided with a valve 16 which may be "cracked" or opened to a very slight degree, so that the extract which is formed in the vessel 12, may flow through this "cracked" valve into the receptacle 17 without permitting the pressure in the vessel 12 to fall materially below that of the source of steam, which, in the illustrative embodiment, is the boiler 10.

A gauge glass 18 may be provided in the outlet pipe 15 and, when the apparatus begins working, a supply of extract may be permitted to accumulate in the lower portion of the outlet 15 while the valve 16 is tightly closed and then the amount of opening of the valve 16 can be regulated so as to maintain a substantially constant level of the extract in the glass 18.

The extract deposited in the vessel 17 may be supplied to the boiler whose incrustation is to be prevented in any suitable manner, as, for instance, by pouring it into the hot well 75 from which the boiler feed water is drawn or supplying it to the feed line. In fact, if desired, the outlet 15 beyond the valve 16 may be connected directly to the boiler feed line.

It will also be obvious that many different forms of valve or other control mechanism may be used to control the outflow of the extract, such as a globe valve or the well-known float-controlled trap.

In carrying out my method, a quantity of 85 flaxseed or the like is placed in a container 13 in the vessel 12 and the cover on the vessel closed. Then the valve in pipe 11 is opened to admit high pressure steam into the vessel 12. The steam is condensed in the vessel and 90 this condensate together with the steam extracts mucilaginous material from the seeds which is carried off by the condensate. This fluid flows through the "cracked" valve 16 into the receptacle 17, from which it may be 95 delivered in any desired manner into the boiler water. As is well known, this mucilaginous extract has the effect of preventing the formation of scale on the internal boiler surfaces.

I claim:

1. The steps in the extraction of the mucilaginous constituents from vegetable seeds which comprise treating the seeds with wet steam under super-atmospheric pressure in a closed vessel and permitting the liquid extract resulting from such treatment to escape to a receptacle at a pressure substantially lower than the pressure in said closed vessel

10 while maintaining the pressure in said closed vessel.

2. The steps in the extraction of the mucilaginous constituents from vegetable seeds which comprise treating the seeds with wet steam under super-atmospheric pressure in a closed vessel and permitting the liquid extract resulting from such treatment to escape substantially continuously to a receptacle at a pressure substantially lower than the pressure in said closed vessel while maintaining

29 the pressure in said closed vessel.

JOSEPH F. SANFTLEBEN.
